FRANK L. GEORGE, OF LOS ANGELES, CALIFORNIA.

ACTION-BRACKET FOR GRAND PIANOS.

1,353,648.

Specification of Letters Patent. Patented Sept. 21, 1920.

Application filed September 9, 1919. Serial No. 322,732.

To all whom it may concern:

Be it known that I, FRANK L. GEORGE, a citizen of the United States, residing at Los Angeles, in the county of Los Angeles and 5 State of California, have invented new and useful Improvements in Action-Brackets for Grand Pianos, of which the following is a specification.

My invention relates to action brackets 10 for grand pianos and consists of the novel features herein shown, described and claimed.

All grand actions of today, among other 15 defects, have one serious condition which is an almost intolerable nuisance to the tuner and repair man, and the time and labor consumed and wasted by these same men in handling this particular piece of work costs 20 somebody many a dollar which should and can now be saved.

Grand actions are so constructed that in order to remove a key to perform half a minute's work the entire action must be removed from the key-frame cleaning every 25 thing away from above the key-board before a key may be removed, and when the work is completed then the entire operation, must be gone through again in replacing the action in position once more; all of which 30 consumes much time in order to be able to remove the key on which to accomplish a few moments' work.

In order to remove the action from the key-frame all screws which hold the five 35 metal brackets firmly to the key-frame must first be removed in order to lift the action clear of the key board so that a key may be removed. Another defect found in the conventional mountings for grand piano ac- 40 tions where all the brackets are firmly screwed down is that of changing the ham- 45 mer-throw, that is the permanent distance from the point of the hammer to the wire which is normally one and three-fourths 50 inches; when it is desired to change this to a greater or less distance with the actions now in use, each and every capstan screw must be turned either up or down until the 55 hammer has been adjusted to the desired distance, then all regulating screws as well as back checks must be carefully looked over to see that they are properly adjusted. This piece of work when performed by an expert regulator requires approximately three hours' time.

Now again the soft pedal operation of the

grand actions now in use is of the shifting type, that is the entire action is shifted sidewise by the pedal, the object being to cause the hammers to strike two unison 60 wires instead of three, and so on, and result in decreasing the volume of sound produced. This system produces several very disagreeable and faulty results; in the first place the entire action-frame and all must 65 be placed into the piano like a drawer in a table and in order to have it slide forth and back must be left loose in the piano and cannot be screwed down securely and permanently; the objections to this are numerous 70 and can readily be imagined.

Again the use of this pedal by the performer seldom throws the action exactly the same distance, resulting in the points of the hammers seldom striking the wires in the 75 same spot and not only causes a very disastrous wearing to the points of the felt hammers but also results in a most displeasing tone known as a woolly tone. Then again, counting from the extreme left or 80 bass end of the piano keyboard, approximately the first twelve hammers strike only one wire each; and approximately the next fifteen hammers strike two wires each; then the remaining hammers strike three wires 85 each. Now, it will readily be understood that when the action is shifted sidewise by the performer for the soft tone effect the result is very disappointing so far as the piano ac- 90 tion is concerned, as the first twelve ham- 95 mers still strike the same one wire each and consequently do not decrease the volume of tone at all. The next named fifteen hammers shift over far enough to strike only one of the two wires struck when in the normal position, therefore decreasing the original 100 volume of tone just fifty per cent. or one-half; then the remaining hammers each shift sidewise far enough to strike two of the original three wires, thereby decreasing the tone volume thirty-three and one-third 105 per cent. or one-third of the normal tone volume; consequently the result is that part of the tone is reduced one-third, another part one-half and still another section none 110 whatever, and were it not for the fact that the pianist studiously endeavors to control the force of his blow upon the keys in order to partially equalize things the result would be entirely disastrous.

My object is to overcome these and other objections.

My action bracket including the means for operating the same by the foot of a performer is called the to-nom-e-ter pedal, meaning tone measurer.

5 The figure is a side elevation of an action bracket or tonometer device embodying the principles of my invention, parts running crosswise of the bracket being shown in section and other parts being broken away and shown in section.

10 The piano key 1, the capstan screw 2 mounted upon the piano key, the wippen 3 resting upon the capstan screw and pivotally connected to the support flange 4 mounted upon the support rail 5, and the action 6 are shown, described and claimed in detail in my companion application for actions for grand pianos, Serial No. 322731.

15 The supporting post 7 is rigidly mounted upon the key-frame 8 by screws 9 and extends upwardly a considerable distance. The metal bracket 10 has a forwardly extending arm 11 connected to the upper end of the support 7 by a screw 12. The base 20 13 is formed integral with the arm 11 and extends horizontally backwardly on a slightly lower level than the arm 11.

25 The expansive coil spring 14 is mounted upon the key-frame 8 just behind the center of the base 13, and the base 13 rests upon the spring 14, there being a lug 15 extending downwardly from the base 13 into the spring 14 to hold the spring in place.

30 The extension 16 extends horizontally backwardly from the base 13 upon a slightly lower level. A felt 17 is mounted upon the key-frame 8. A soft pedal screw 18 is tapped upwardly through the extension 16 and has a head 19 upon its lower end to engage the felt 17 and a kerf 20 in its upper end, so that the screw may be manipulated with a screw-driver or the like.

35 The normal screw 21 is inserted downwardly through a felt 22 and through a large opening 23 in the extension 16 and tapped into the key-frame 8, so that by manipulating the normal screw 21 the spring 14 is expanded or contracted to regulate the normal position of the action 6 relative to the piano wires, and so that by manipulating the soft pedal screw 18 the shift of the action 6 downwardly under the influence of the soft pedal may be accurately adjusted.

40 45 50 55 60 65 A soft pedal bar 24 extends upwardly through a slot in the key-frame 8 and above the key-frame 8 to a point above the rear end of the extension 16, and an arm 25 is bent forwardly from the upper end of the pedal bar 24 to engage on top of the rear end of the extension 16, so that when the soft pedal is operated the extension 16 will be pulled downwardly against the tension of the spring 14 until the head 19 strikes the felt 17, as shown in dotted lines, and this

70 operation lowers the entire piano action 6 relative to the piano wires. The soft pedal bar 24 is adjustable where it connects to the trap action on the under side of the piano. This construction is not shown.

75 When the pedal bar 24 has been properly adjusted and the soft pedal screw 18 and the normal screw 21 properly adjusted and the performer operates the soft pedal, the trap action pulls down the pedal bar 24, thereby pulling down the bracket extension 16 and swings the entire action bracket upon the screw 12.

80 A rear pedestal 26 extends upwardly from the rear end of the base 13 and has a right-angled seat 27 in which the support rail 5 is mounted. A front pedestal 28 extends upwardly from the forward end of the base 13 and the rear end of the arm 11 and has a seat 29 in which the regulating rail 30 is mounted and secured in place by a screw 31, and the pedestal 28 has a seat 32 in its upper end in which the hammer flange rail 33 is mounted and secured in place by a screw 34. Thus the support rail 5, the regulating rail 30 and the hammer flange rail 33 are carried by the bracket 10 and, of course, the action 6 is carried by the support rail 5, the regulating rail 30 and the hammer flange rail 33, so that as the bracket 90 95 100 swings upon the screw 12 the action goes up and down to regulate the position of the hammer 35 relative to the piano wire.

105 The arm 36 extends upwardly and backwardly from the rear end of the arm 11. The arm 37 extends forwardly and upwardly from the pedestal 26 and joins with the rear end of the arm 36. The arm 38 extends backwardly and downwardly from the seat 32 and the upper end of the pedestal 28 and joins with the arms 36 and 37. The arm 39 extends upwardly from the pedestal 26. The arm 40 extends backwardly and upwardly from the rear end of the arm 38 and joins with the upper end of the arm 110 115 120 125 130 39, and a bearing 41 is formed at the upper ends of the arms 39 and 40. The arms 39 and 40 and the bearing 41 are for the purpose of connecting a touch regulator which I have shown, described and claimed in a companion application, Serial No. 322730, and these parts are unnecessary to the action bracket where the touch regulator is not used.

130 When the rear end of the action bracket 120 125 130 135 140 145 150 155 160 165 170 175 180 185 190 195 200 205 210 215 220 225 230 235 240 245 250 255 260 265 270 275 280 285 290 295 300 305 310 portion to the relative distance from the screw 12 and the regulating rail 30 is also moved downwardly.

Thus I secure a soft pedal action through

- 5 the action bracket 10 which raises and lowers the action 6 instead of shifting the action sidewise. The hammer stroke is readily adjusted to the desired distance up or down by manipulating the normal screw 10 21. If desired to secure the soft pedal effect continuously for a time the screw 21 may be properly adjusted and it will not be necessary to operate the soft pedal.

By removing the screw 21 the bracket 10 carrying the entire action may be swung upwardly and forwardly on the screw 12 as far as desired and then the key 1 may be quickly and easily lifted from the key-frame for repair or for any other purpose, and by 20 removing the screws 12 and 21 the bracket and action may be removed.

Thus I have produced an action bracket adapted to be pivotally mounted at its forward end and adapted to be connected to a 25 soft pedal at its rear end and having a spring for raising the bracket to normal position, an adjusting screw for limiting the downward swing, and an adjusting screw for limiting the upward swing, the bracket 30 being adapted to carry the entire action.

Various changes may be made without departing from the spirit of my invention as claimed.

I claim:

35 1. An action bracket adapted to be pivotally mounted at its forward end, resilient means supporting the rear end of the bracket, an adjusting screw limiting the downward movement of the rear end, an adjusting screw limiting the upward movement of the rear end of the bracket, and means operatively connecting the rear end to a soft pedal.

2. An action bracket adapted to carry an 45 action and adapted to be pivotally mounted at its forward end, means yieldingly supporting the rear end of the bracket, adjustable means limiting the downward movement of the rear end of the bracket, adjustable means limiting the upward movement of the rear end of the bracket, and means operatively connecting the rear end of the bracket to a soft pedal.

3. An action bracket adapted to be pivotally mounted at its forward end, a spring supporting the rear end of the bracket, an adjusting screw limiting the downward movement of the rear end of the bracket,

and an adjusting screw limiting the upward movement of the rear end of the bracket. 60

4. An action bracket for grand pianos, comprising a bracket adapted to carry an action comprising a mechanism embodying hammers and pivotally mounted on a proper base; a spring supporting the rear end of the bracket; and adjustable means for limiting the upward movement of the rear end of the bracket, whereby the distance of the hammers to the strings may be regulated and a desired effect in total volume may be 70 produced.

5. An action bracket for grand pianos comprising a bracket adapted to carry an action comprising a mechanism embodying hammers and pivotally mounted on a proper 75 base, springs disposed to carry the weight of the action with the hammers close to the piano strings, in which position a pianissimo effect is produced, and means operating to draw the bracket downwardly, whereby the 80 hammers will be moved toward the strings and decrease the volume of sound to the desired degree.

6. An action bracket for grand pianos, comprising a bracket adapted to carry an 85 action comprising a mechanism embodying hammers, said bracket being pivotally mounted at its forward end; a spring removably supporting the rear end of the bracket; and removable adjusting means 90 limiting the upward movement of the rear end of the bracket, the bracket being, on removal of the adjusting means, free to swing on its pivot at the forward end, thereby permitting access to the keys of the piano 95 for removal or repair.

7. An action bracket for grand pianos, comprising a bracket adapted to carry an action comprising a mechanism embodying hammers; a removable pivot supporting the 100 forward end of the bracket; a removable spring supporting the rear end of the bracket; and adjustable and removable means for limiting the upward movement of the rear end of the bracket, said bracket 105 and said spring being the only supporting means of the bracket, so that on removal of the means for limiting the upward movement of the rear end of the bracket, and removal of the pivot, the bracket and the 110 action carried thereby may be removed from the piano.

In testimony whereof I have signed my name to this specification.

FRANK L. GEORGE.
